(No Model.)

L. A. H. GRENELLE.
WINDOW CURTAIN HOLDER.

No. 464,499.

Patented Dec. 8, 1891.

UNITED STATES PATENT OFFICE.

LINNIE A. H. GRENELLE, OF HAMPTON, IOWA.

WINDOW-CURTAIN HOLDER.

SPECIFICATION forming part of Letters Patent No. 464,499, dated December 8, 1891.

Application filed August 20, 1891. Serial No. 403,201. (No model.)

To all whom it may concern:

Be it known that I, LINNIE A. H. GRENELLE, a citizen of the United States, residing at Hampton, in the county of Franklin and State 5 of Iowa, have invented certain new and useful Improvements in Window-Curtain Holders; and I do hereby declare the following to be a full, clear, and exact description of the invention, such as will enable others skilled 10 in the art to which it appertains to make and use the same.

My invention consists in a curtain-holder adapted to hold or drape lace curtains at the sides of a window, the same comprising fastening branches for bearing against the face 15 of the window-frame, and an open-work projecting front portion connected to said branch arms by bow-shaped bends, the whole being formed of one piece of wire, and presenting 20 to the eye an ornamental form, preferably that of a clover-leaf, as will be hereinafter described, and specifically claimed.

In the accompanying drawings, Figure 1 is a perspective view of a window-frame with 25 curtains held or draped with my improved holder; and Fig. 2 is a perspective view, on an enlarged scale, of the improved curtain holder.

The curtain-holder A is made of a single 30 piece of wire, which is bent at its ends a, so as to form eyes through which are passed fastening-screws, as illustrated. A short distance from these eyes nearly right-angular bends b are made in the rear branches a' of the wire, so as to form shoulders b', one on 35 each branch of the holder. The wire is then bent into bows c c, said bows lying nearly horizontal, and into two vertical bows d, and a nearly-circular loop e, the latter connecting the two vertical bows by graceful curves. 40 There are similar curves connecting the horizontal bows with the vertical bows. The three last bends are preferably of the ornamental form of a clover-leaf. By this construction those portions of the holder which 45 are inside of the angular bends are thrown out from the window-frame sufficiently far to allow of an ordinary curtain or shade being applied to the window and manipulated without any obstruction from the holder, and a

space for a lace curtain to be applied between 50 the front and rear portions of the holder is afforded, while at the same time the said curtain can be bunched up and drawn through the space formed by the three bends made in the front portion of the holder, and on this 55 bunched portion a ribbon bow g can be fastened, and such bow made to serve the two-fold purpose of holding the curtain in its bunched form and concealing the holder proper, while it presents an ornamental finish. 60

The within-described invention is very simple, durable, and convenient of application, only two screws being required to fasten it in position, and it being made of round wire and of skeleton form, it is not liable to catch or 65 hold dust. Neither is there any danger of its tearing or wearing lace or other goods used in draping a window. It is also easy to keep clean and bright, and with very slight expense can be rebronzed, gilded, or painted. It being 70 springy, it is not liable to be broken by a fall or by being struck in dusting and in moving the furniture of a room.

I do not confine my invention to the special manner of use described and shown—namely, 75 drawing a small portion of the curtain some distance from its lower end through the holder, and spreading it out to form rosette drapery, for, by looping a small portion of the curtain on each side of the rosette the butterfly drapery can be produced, and by making 80 a bow of one yard of No. 9 or 12 ribbon and securing it to the holder with a pin the holder will be covered, and at the same time the effect of the curtain being held back by 85 a ribbon will be produced, while a saving of expense of one and a half to three yards of ribbon to a window will be effected, and the trouble of tying and untying the ribbon avoided. 90

What I claim as my invention is—

1. The within-described curtain-holder having two attaching branches, two bowed portions in about a horizontal plane, and two bowed portions in about a vertical plane connected by a vertical looped portion in about a vertical plane, substantially as described. 95

2. The curtain-holder made of a single

piece of wire bent to form a space for the lace curtain between the front and rear branches of the holder and to form a space for drawing a portion of the curtain through the 5 front portion of the holder, so that it may be secured in a bunched form in front of the holder, substantially as and for the purpose described.

In testimony whereof I hereunto affix my signature in presence of two witnesses.

LINNIE A. H. GRENELLE.
